E. S. SCRIPTURE.

Axle-Collar.

No. { 1,495, {
32,499.

Patented June 4, 1861.

Inventor:
Eliphalet S. Scripture

UNITED STATES PATENT OFFICE.

ELIPHALET S. SCRIPTURE, OF NEW YORK, N. Y., ASSIGNOR TO HIMSELF AND EDWARD WHITE, OF SAME PLACE.

AXLE-COLLAR.

Specification of Letters Patent No. 32,499, dated June 4, 1861.

To all whom it may concern:

Be it known that I, ELIPHALET S. SCRIP-
TURE, (assignor to himself and Edward
White,) of the city, county, and State of
5 New York, have invented new and useful
Improvements in Axle-Collars; and I do
hereby declare that the following is a full,
clear, and exact description of the same, refer-
ence being had to the annexed drawings,
10 making a part of this specification, in
which—

Figure 1 shows a view of axle, and axle
arm, with my improved collar and slide
packers attached. Fig. 2, cut section of the
15 same; Fig. 3, top view of divided moon
plate employed; Fig. 4, front view of the
same; Fig. 5, top view of slide packer used;
Fig. 6, an edge view of the same; Fig. 7 is
20 a back surface view of my improved collar,
showing the perforated cellular flange em-
ployed; Fig. 8 is a cut section of the same;
Fig. 9 is a front face view of the same oppo-
site side of flange, as shown in Fig. 7.

Similar letters of reference indicate cor-
25 responding parts in all the figures.

This invention consists in a novel mode of
constructing the shoulder or holding flange
with its accompanying sectional slide pack-
ers, as hereinafter shown, whereby impor-
30 tant advantages are attained and secured,
such as getting greater strength from the
use of a given amount of metal, at the same
time securing the convenience of applying
cheap and durable packing, also, that of
35 conveniently applying and retaining grease,
or other lubricating matter, the same being
allowed to circulate freely through said
holding flange or shoulder, instead of hav-
ing to pass over it in order to reach the
40 moon plate, or other coupling, or back fas-
tening employed, the same being protected
by the use of the slide packers, accompanied
with gasket, moon plate, or other back fas-
tenings, provided with protecting flange—
45 by which arrangement, also, dust and grit
are effectually excluded from the wearing
parts, all of which advantages greatly di-
minish expense and trouble.

To enable those skilled in the art to fully
50 understand and construct my improvements
or invention, I will proceed to describe it.

In Fig. 1 letters A A' represent an axle
arm, and a portion of its main bar, or body,
B' the holding flange or collar, with its ter-
55 minating neck, or tube, B B, at which place

may be seen a bear's mouth slit; C C, are sec-
tional slide packers, which are made in two
parts, not only for the convenience of ap-
plying and operating, but to allow of the
yielding, or contracting, of the same, in con-
junction with the bear's mouth collar neck,
under the power of the bolt and nut D d in
case of shrinkage of timber or other causes.
E' E represents the hub coupling, which
in this case I employ the divided moon plate,
60 arranged nearly in accordance with that of
my patent of December 18th 1855, as a con-
venient substitute for the common male axle
moon plate, back screw, or other back fasten-
ing couplings either of which may be ar-
ranged to go, and be used with the above
improved collar and sectional packers, gas-
ket, &c. e e² represent the joints, or bolt
apertures, catch, &c., which bolts x x, are
there represented as being short, though are
70 to be long enough to pass through a carriage
wheel hub, when put to use therewith.

In Fig. 2 A A' shows the axle arm, and
its continuation as set forth in Fig. 1; B' B'
represents the holding flange (or collar) at 80
which place may be seen its periphery, in
flange form. b' b' represent its cells and
center flange, at which place are represented
holes for grease circulation, and for the pur-
pose of holding and securing packing, &c. 85
C C, slide packers. D, the bolt passing
through the axle, slide packers, and collar
neck, or tube, securing the same thereto, as
well as to serve to loosen the sectional pack-
ers c c, when required to be slid back or 90
forth, or taken entirely off, (as the case may
be,) and again securing them, as well as the
collar neck snugly to the axle. E E', di-
vided moon plate coupling, e, the back end
of the catch, near which is shown the con-
95 cave, or half hole, that shuts over the bolt X.
F F shows a gasket beneath the back pro-
jecting flange of coupling E E' and directly
forward of the slide packer heads c c. This
gasket serves to check and retain the grease 100
as it tends to flow back from the cells b' b',
an operation which will be augmented by the
action of the hub box (which is to be capped
air tight at its outer end) as it will have
play back and forth upon the axle arm when
105 the vehicle is in motion, serving in the
capacity of an air pump in forcing the oil
or grease through the holes at b' b' in to
the back cells, there maintaining a supply of
lubricating matter that will ever keep 110

smooth and glib that part which is the first to get dry and wear out in the old plan of back fastening collars.

In Fig. 3 letter E represents the inner side 5 of the divided moon plate E' showing its back projecting flange within which the gasket F F and packer head c, (as shown in Fig. 2). e e' shows the catch or hook lock as the coupling plate is closed together and secured by bolt X.

Fig. 4 is a front view of moon plate, as being partly open, letters E E showing the outer plate circle while e² shows the side which is made a sort of hinge joint, by one 15 of the hub bolts X serving as a pintle to the hinge joint, while at e e' the lock part and opposite bolt cavities are shown.

In Fig. 5 letter C, shows a top view of sectional slide packer; C' represents a bolt 20 slot in the same, and c the packer head or rim.

In Fig. 6 at letters C C are shown the front, or forward part of packer head.

In Fig. 7 b', represents the short cells in 25 the back surface of the collar b b, showing the long cells, as filled with leather packing; while b² shows the cells ready to receive the packing showing two holes to admit of fastening the same in its place.

In Fig. 8 B' B' shows the periphery of 30 collar shoulder in flange form, b' b' showing the center flange and situation of holes through the same, B the collar neck or tube, Fig. 9 being a front face view of collar, 35 opposite side of flange, as shown in Fig. 7, letters b' b' showing the short cells and

grease holes through the same as also shown in Fig. 7, b² showing the long, or packing cells, with two holes through center flange, 40 b b showing cells filled with leather packing, secured by wooden pegs, passing through the same and the holes in center flange, taking the leather in opposite cell, thereby securing the same permanently, which it is intended to have last as long as the wagon, or carriage may endure.

I do not claim the moon plate coupling E E', as used and set forth in this case, nor do I claim the gasket, used in conjunction therewith, the same having been adopted 50 and described in my patent axle coupling of December 18th 1855.

What I do claim as new, and desire to secure by Letters Patent, is—

1. The metallic cellular collar, made, in 55 the manner shown, and for the purpose, or purposes herein set forth and described.

2. The sectional slide packers, made in the manner, and for the purpose herein described.

3. The metallic cellular collar, the sectional slide packer, with its flange in combination with the protecting collar, flange, and gasket, when the same shall be used, substantially in the manner as shown, and for 60 the purpose or purposes herein set forth and described.

ELIPHALET S. SCRIPTURE.
